VENETIAN BLIND HEAD BAR

Samuel Hammer, Brooklyn, N. Y., assignor to
United Metal Box Co., Inc., Brooklyn, N. Y., a
corporation of New York

Application April 26, 1935, Serial No. 18,300

5 Claims. (Cl. 156—17)

This invention relates to improvements in the construction and operation of Venetian blinds.

An important object of the invention is to provide as an article of manufacture a device for supporting the slats of a Venetian blind and concealing the usual slat lifting cord guide pulleys, slat tilting mechanism, and lifting cord locking mechanism, in a unitary head bar structure.

Another object of the invention is to provide an improved means for using what may be described as single supporting tapes, as distinguished from double or so-called ladder tapes heretofore used in the manufacture of such blinds and to provide means for securely fastening the tapes to the edge 10 faces of the slats by a clip or other fastening means which may be easily removed as occasion requires.

Another object of the invention is to provide an improved mechanism for tilting the slats of the blind, as well as an improved mechanism for locking the lifting cords.

Other objects of my invention will either become apparent or be specifically referred to in the following description wherein reference is made to the accompanying drawing in which

Figure 1 is a front elevational view of my improved slat support and head bar construction.

Figure 2 is a plan view of the structure shown in Figure 1.

Figure 3 is an end view of the structure shown in Figure 1 as seen from the left-hand end thereof.

Figure 4 is a view taken on the line 4—4 of Figure 1 and looking in the direction of the arrows.

Figure 5 is a view of the tilting mechanism taken on the line 5—5 of Figure 3 and looking in the direction of the arrows.

Figure 5a is a sectional view taken on line 5a—5a of Figure 5.

Figure 6 is a view taken on line 6—6 of Figure 1.

Figures 7 and 7a may be described as views showing, in detail, the parts of a cord guide pulley.

Figure 8 is an assembly view of a cord guide pulley mounted upon the head bar.

Figures 9, 9a and 9b are views showing elevation and end views of a double guide pulley and mounting therefor.

Figures 10, 11 and 12 show the manner of employing a spring clip for fastening the slat supporting tapes to the edge face of the slats in such a way that the over-all bundling height of the slats when the blind is raised to the top of the window is no greater than the summation of the

thickness of the slats. In some respects, this clip construction is an improvement over the invention defined and claimed in my copending application Serial No. 726,225 filed May 18, 1934.

Figure 13 illustrates how a difference in slat thickness affects the amount a slat may be tilted.

Referring now to Figures 1 and 2, it will be seen that my blind comprises a head bar 10 adapted to be mounted in any suitable manner at the top of a window frame 10a by supporting brackets 11 and 12. The head bar 10 is essentially a channel member comprising a web 13, front and rear walls 14 and flanges 15 formed by bending the upper edges of the walls toward one another, see Figure 8. The brackets 11 and 12 are preferably constructed similar to each other except that they are appropriately modified for use as supports for the right and left-hand ends of the head bar, respectively. The bracket 11, for instance, is formed from a single sheet metal stamping comprising a side 18 and a back 19 bent at right angles to each other. Screw holes 20 are formed in either or both the side 18 and back 19 for mounting the bracket in any suitable position at the top of a window. A front 21 is cut integrally from the same piece of material as the side 18 and bent in the same direction as the back 19, that is, at right angles to the side 18 and parallel to the back 19. A locking tongue 22, formed integral with the edge of the back 19 remote from that at which it joins the side 18, is bent at right angles to the back and toward the front 21.

At each end of the front wall of the bar 10 a screw slot 23, see Figure 1, is formed and at each end of the rear wall an opening 24 is formed. The bracket 11 and head bar 10 as seen in Figure 1 may be assembled by lifting the end of the rear wall 14 upwardly between the free end of the locking tongue 22 and the front 21, and thereafter moving the same rearwardly into supporting engagement with the bracket so that the locking tongue 22 projects through the opening 24 and the slot 23 is disposed over the hole for a screw 26 in the front 21 with the flange 15 of the front wall 14 resting upon the front 21. The head bar is secured in position by a screw 26. Before the screw 26 is in place the bracket may be adjusted longitudinally of the head bar an amount equal to the length of the opening 24. A greater adjustment is prevented by the engagement of the tongue 22 with the ends of the opening 24. For this reason the tongue 22 is referred to as a locking tongue. In a device of this kind the locking tongue prevents the brackets and head bar from being assembled when the brackets

20

25

35

40

45

50

55

are mounted at a distance from one another greater than that which would permit the bar to be securely supported by the brackets. Furthermore, if the brackets are mounted too far apart and one end of the head bar is assembled in a bracket it is not possible, because of the locking tongue, to pull the assembled end of the head bar out of the bracket in an effort to support the other end of the bar on the other bracket. Hence 10 the combination of a head bar and locking tongue of this kind prevents injury to a person attempting to install a Venetian blind on brackets which are not properly spaced with respect to one another. It will also be seen from Figures 4 and 6, 15 that the forward end of the locking tongue is formed with a hook 27 so that if the flange 15 inadvertently slips off the front 21 before the screw 26 is placed in the end of the head bar, the hook will engage and retain the head bar in elevated position. The location of the top of the locking tongue 22 and the upper edge of the hole 24 is such that the tongue 22 will properly support the back part of the head bar when the screw 26 secures the bar to the bracket. 20

25 Referring again to Figure 1, it will be understood that the series of slats 30, 31, 32, 33 terminating in a lowermost slat (not shown) are supported from the tilting slat 30 by flexible members 34 made of any suitable material, but preferably fabric tapes. The tapes 34 are secured to the edges of the slats in a manner to be herein-after described. Suffice it to say for the moment that said securing means cooperates with apertures 35, see Figure 11, formed in the edge face 30 of the slats. All of the slats and the head bar are perforated as at 36 to permit the passage therethrough of raising and lowering cords 37 and 38 which are secured to the lowermost slat, in the usual way.

40 Guide pulleys 40, 41 and 42, mounted on the head bar are provided to position and guide the cords 37 and 38 when they are pulled from their vertical positions to one side of the window where they pass downwardly near a locking pawl 43, 45 to be hereinafter described, which is adapted to grip the cords and thereby hold the blind in any desired position of elevation.

Referring now to Figures 3 and 5a it will be seen that the slats 30 to 33 are preferably made 50 of strips of sheet metal stiffened by having the edges thereof bent over with respect to the plane of the strip. From the standpoint of slat thickness the formation of this stiffening edge gives to the slats that appearance of stability to which 55 one may have become accustomed in seeing blinds having slats made of wood. In the slats here shown the stiffening edges are of tubular formation, and in the case of the uppermost slat 30, these tubes are employed in combination with 60 means for supporting and tilting the slats, see Figures 5 and 5a.

My unitary head bar structure comprises in addition to the head bar above described a pair of depending housings 45 and 46 for rotatably 65 supporting the upper slat at its right and left hand ends respectively and for mounting and concealing, respectively, a slat tilting mechanism and a lifting cord locking mechanism. The housings 45 and 46 are also made of sheet metal 70 formed to have a generally channel shaped cross section and comprising a web portion 47 substantially the same width as the web 13 of the head bar 10 but with a front wall portion 48 narrower than that of the head bar, and a rear wall 49. 75 One end of the web 47 is bent at right angles, as

at 50, to provide means for welding or otherwise securing the housing 45 to the web 13 of the head bar 10 so that the web 13 and web 47 are disposed at right angles to one another and the front walls 14 of the head bar 10 and 48 of the 5 housing are disposed in the same plane. This construction forms a more or less regular shaped housing unit by which the usual Venetian blind hardware is attractively concealed. A tiltable or trunnion-like mounting member 51, having a 10 shank 52 is rotatably mounted in the web 47 and rigidly secured by any suitable means to a pulley 53 about which is disposed a tilting cord 54 secured intermediate its ends, as at 55, to the periphery of said pulley, see Fig. 3. Stops 56 15 and 57 are provided on the pulley 53 to cooperate with a stop 58 on the web 47, see Fig. 6, to prevent the tilting mechanism from making more than one revolution. A spring washer 59 is disposed between the pulley 53 and the inside of the 20 housing 45 to frictionally retain the pulley in any position to which it may be set. In the device here shown the tilting member 51 is provided with a prong 60 disposed at each end thereof and adapted to fit respectively into the tubular edges formed on the uppermost slat 30, see Figures 5 and 5a. The other end of the slat 30 is similarly carried by a rotatable tilting member mounted in a web 61 of the right hand housing 46. 25

The housing 46 is mounted on the web of the 30 head bar by means of an extension 62 to which is first secured a double guide pulley 42, like that shown in Figures 9, 9a and 9b. It will be seen that the housing 46 comprises a front wall 63 from which a rear wall 64, see Figure 2, is 35 bent to form an enclosure 65 for the locking pawl 43. The web 61 opposite the locking pawl is cut away as at 67, see Figure 4, and bent to form a fixed abutment 68, see Figure 1, so that when the lifting cords 37 and 38 pass through the 40 housing 46 the locking pawl 43 and fixed abutment 68 will be disposed respectively proximate the opening 67. It will be seen from Figures 1 and 4 that when the lifting cords are held out of engagement with the locking pawl 43 by being moved slightly to the left, the pawl will drop by gravity to the bottom of the housing 46. When the cords are guided by the operator they will run freely past the pawl 43 and permit the blind to be lowered. However, when the cords 50 move toward the pawl 43, under the influence of the free falling blind and without the guiding restraint of the operator, the cords will momentarily acquire such speed as to be thrown outwardly into engagement with the gripping 55 edges of the pawl 43 and lift the pawl until the cords are pinched thereby against the abutment 68. It will be seen that a downward pull on the cords will release the gripping action of the pawl and permit an operator to raise or lower the 60 blind according to the manner in which the cords are guided.

Figures 7, 7a and 8 illustrate how the guide pulleys are formed from two cup-shaped stampings 70 and 71 of such size that the latter fits 65 into the former. The stamping 70 is formed with a peripheral flange 72 for reasons to be hereinafter described. Each of these stampings is formed with a central hole 73 having a bearing 74 for mounting the same on a shaft 75. 70 A washer 76 of oil-soaked felt or other lubricating material is disposed between the stampings before they are assembled. Figure 8 illustrates the assembled pulley when the same is mounted in an angular position such that the cord 37 is 75

constrained to run against the guide flange 72 of the pulley.

The pulley mounting 78, see Figure 2, is formed of sheet metal with shaft bearings 79 punched inwardly from the sides thereof. Lugs 80 and 81 are formed above the bearings 79 to hold the ends of the shaft in position. After the device is assembled, with the ends of the shaft 75 pressed into position past the lugs and onto the bearings 79, as shown in Figures 8 and 9, the bracket is then welded to the head bar. A guide lug 82, see Figure 8, is formed in the side wall of the single pulley mountings to prevent the cord from slipping off the pulley at the side remote from the flange. Referring now to Figures 10, 11 and 12 it will be seen that the tapes 34 are secured to the edge face of the slats by means of a clip 85 adapted to pass through the tape like a staple. This clip is preferably made of spring wire having the ends thereof bent to form arms 86 and 87 adapted to fit into the perforations 35 in the edge face of the slat. The wire at the end portions of the arms is bent upon itself, so to speak, so that the ends form with the arms a recess 88 at each side of the head of the clip. It will be understood that the proportions of the clip 85 perforations 35 are such that when the clip is disposed in the perforations it may be easily flexed sufficiently to unhook one end thereof so that it can be removed from the perforation whereupon the other end may be removed also.

Figure 13 illustrates how a difference in slat thickness affects the amount a slat may be tilted. For instance the thick slat 90 is shown tilted as far as can be because of the engagement between the edge of the hole therein and the raising and lowering of the cord 37. The slat 91 may, however, be tilted slightly further due to its reduced thickness.

While I have described what seems now to be the preferred embodiments of my invention, it is conceivable that various modifications in the configuration, composition and disposition of the component elements going to make up the same may occur to those skilled in the art, and no limitation is intended by the phraseology of the foregoing description or illustrations in the accompanying drawings.

What is claimed is:

1. A head bar for a Venetian blind having a web and a front wall extending upwardly from said web; and a housing depending from each end of said head bar; each of said housings comprising a web forming in effect a vertically disposed portion of said head bar web, and a front wall disposed in the plane of the front wall of the head bar.

2. A head bar for a Venetian blind having a web and a front wall extending upwardly from, and longitudinally beyond the ends of, the front edge of said web; and a housing depending from

each end of said head bar; each of said housings comprising a web forming in effect a vertically disposed portion of said head bar web, and a front wall disposed in the plane of the front wall of the head bar and forming with the latter side portions of said structure.

3. A sheet metal head bar for a Venetian blind of channel shaped cross section having a web and a front wall extending upwardly from the front edge of said web; and a sheet metal housing depending from each end of said head bar; each of said housings comprising a web forming in effect a vertically disposed portion of said head bar web; and a front wall disposed at the end of, and in the plane of, the front wall of the head bar forming with the latter the side portions of said U-shaped structure.

4. An inverted U-shaped structure for supporting the slats of a Venetian blind and concealing the slat lifting cord guide pulleys, a slat tilting mechanism, and a portion of the slat lifting cord, comprising in combination a head bar having a web and a front wall extending upwardly from said web; and a housing secured to and depending from each end of said head bar; each of said housings comprising a web of approximately the same width as the web of the head bar and forming in effect a vertically disposed portion of said head bar web, and a front wall disposed in the plane of the front wall of the head bar, means for securing each housing to an end of said head bar, each of said housing webs being adapted to support a tiltable member, one of which members comprises a pulley, and each said housing forming an opening from which two cords are adapted to hang downwardly from a point immediately behind the plane of the front wall of said housing.

5. A hollow head bar structure for supporting the slats of a Venetian blind and concealing the slat lifting cord guide pulleys, a slat tilting mechanism, and a lifting cord locking mechanism comprising in combination a sheet metal head bar of channel shaped cross section having a web and a front wall extending upwardly from the front edge of the web and overhanging the ends thereof, a housing depending from each end of said head bar, each of said housings comprising a web of approximately the same width as the web of the head bar and forming in effect a downwardly disposed portion of said head bar web, and a front wall disposed in the plane of the front wall of the head bar, each of said housing webs being adapted to support one end of a slat through the medium of a tiltable member, one of which members comprises a pulley, and each of said housings forming an opening from which two cords are adapted to hang downwardly proximate the end of the slat and in a plane forward of the front edge of said slat.

SAMUEL HAMMER.
